UNITED STATES PATENT OFFICE.

ELMER E. VAN WIE, OF LONG BEACH, CALIFORNIA.

BUILDING CONSTRUCTION.

Application filed January 25, 1926. Serial No. 83,534.

This invention relates to building construction.

The general object of the invention is to provide an improved building construction wherein unitary blocks are used.

A specific object of the invention is to provide a novel wall composed of a plurality of similar units.

A further object of the invention is to provide an improved building block.

Another object of the invention is to provide a building structure made of units comprising front and back members and wherein the front and back members are united by interlocking members arranged in a novel manner to form a rigid structure.

Other objects of the invention will be apparent from the following description taken in connection with the accompanying drawings wherein:

Fig. 1 is a side elevation of a wall made from my improved blocks, with one face of the wall removed to show the interlocking relation of the blocks;

Fig. 2 is a horizontal sectional view through a corner of a wall embodying the features of my invention;

Fig. 3 is a top plan view of a block or unit embodying the features of my invention;

Fig. 4 is a top plan view of a half block;

Fig. 5 is a similar view showing an end block;

Fig. 6 is a view similar to Fig. 1 showing another arrangement of the locking members on the blocks;

Fig. 7 is a perspective view of one of the blocks shown in Fig. 6;

Fig. 8 is a cross sectional view of one of the blocks embodying the features of my invention wherein one face of the block is provided with a rounded surface;

Fig. 9 is a view similar to Fig. 1 showing the blocks with the front and back faces thereof arranged diamond fashion;

Fig. 10 is a perspective view of a whole block;

Fig. 11 is a perspective view of a half block wherein the faces are arranged to produce the diamond effect;

Fig. 12 is a perspective view of a corner block of the diamond type;

Fig. 13 is a plan view, partly in section, of a wall made from my blocks shown in Fig. 6, showing means for connecting the walls at a corner;

Fig. 14 is a view similar to Fig. 13 showing another connecting means;

Fig. 15 is a perspective view showing a corner block;

Fig. 16 is a perspective view of a single faced block;

Fig. 17 is a view similar to Fig. 1 showing a wall made of the blocks shown in Fig. 16, with the front and back faces extending at right angles to each other;

Fig. 18 is a perspective view; and

Figs. 19 and 20 are end views of blocks wherein the intermediate members are arranged transverse to the front and back members, and

Fig. 21 is a fragmentary view of a portion of a silo, embodying the features of my invention.

Referring to the drawings by reference characters, I have indicated a wall embodying the features of my invention generally at 10. This wall in the preferred form is made from a plurality of individual blocks 11.

Each block is composed of a front member 12, a rear member 14 and a pair of interlocking end members 15. The outer faces of the front and back members 12 and 14 are preferably plane and parallel and the end members 15 are arranged between the front and back members.

The members are shown as connected by fastening means 16 which may be metal members or may be of any other desired character.

In the practice of my invention I may make the blocks of wood or I may make the front and back members of cementitious material and the interlocking members 15 of wood or I may make all of the members of cementitious material or all of the members of wood and I wish it to be understood that I do not wish to be limited to the particular material from which my block is to be made.

Referring again to the drawings it will be noted that the interlocking members 15 have their upper ends 17 projecting above the top of the front and back members while the lower ends 18 project below the bottom of the front and back members. The total length of the interlocking members 15 is preferably less than twice the length of the front and back members so that when the blocks are arranged in interlocking relation to form a wall there will be a space 19 between the ends of the interlocking members

15 so that a proper engagement of the front and back members will be effected.

In constructing the wall the blocks are laid in courses with the vertical joints staggered and with the interlocking members in vertical alignment but out of engagement with each other as shown in Fig. 1 wherein the front member has been removed to show the interlocking arrangement.

10 In constructing the wall I preferably arrange a plurality of blocks in interlocking relation and place reinforcing members 20 upon the connecting member 16. This done, I may proceed to place a cementitious filling 21 as shown in Fig. 2 within the hollow spaces afforded by the blocks. This cementitious filling is poured around collapsible mold members to provide cavities 22 so that good heating and cooling insulation properties are provided.

15 The members 16 are preferably nails or similar fastening members and in constructing a block I prefer to first insert the nails in the interlocking members 15 after which 25 the front and back members may be cast about the nail heads to thus provide a rigid structure. It will be understood that other methods of assembly may be used if desired, however.

20 In Fig. 3 I have shown a hollow block of the character described while in Fig. 4 I show a half block wherein but one of the fastening members 15 is employed.

In Fig. 5 I show a corner block wherein 25 the back member 14 is the length of a full block length while the front member 23 has an end portion 24 which will extend beyond the inner portion 14 as shown in Fig. 2 to provide a corner member which will engage 40 the end of a block laid at right angles to the face 23.

Instead of arranging the interlocking members with their locking ends projecting above and below the front and back members, I may provide a construction as shown 45 in Figs. 6 and 7 wherein the front members 25 are connected to the rear members 26 by interlocking members 27 which are held in spaced relation by means such as nails 28.

50 The members 27 in this construction do not extend below the bottom of the front and back members 26 but extend above this member a distance somewhat less than the width of the front of the block so that when the 55 blocks are interlocked they will assume the position shown in Fig. 6. In this figure the top block 28 is shown as reversed as this construction would be desirable in finishing a wall. Vertical and horizontal reinforcing 60 members 29 may be provided for this arrangement of interlocking blocks if desired.

In Fig. 8 a rear member 14 is shown. The interlocking members 15 are of the construction heretofore mentioned. The front 65 member 30 differs slightly in that this mem-

ber is rounded on its exposed surface to provide a column-like effect. On this surface I may provide a veneer 31 or other embellishment if desired.

In Figs. 9, 10 and 11 I show the wall constructed of blocks made with front members 32, rear members 33, and interlocking members 34 which are spaced from the front and back members and are fastened to the front and back members by fastening means 36. 70 In this arrangement the front and back members 32 are arranged so that the locking members 34 are parallel to a diagonal to the front and back members. With this construction a diamond effect is produced in the wall which is in many cases quite desirable. In Fig. 10 a front block is shown while in Fig. 11 a half block is shown.

75 In Fig. 12 I show a corner block of the diamond type which comprises an L-shaped member 35 which has a plurality of locking members 36 secured thereto. This block may be used to complete corners of walls made with the exposed faces of the block arranged in the diamond pattern.

80 In Fig. 13 I show a horizontal section of a corner made with blocks of the character shown in Figs. 6 and 7. This corner is made by securing boards 40 upon the ends of the front and back members 25 and 26, also by 85 securing them by fastening means 41 to the interlocking members 27. After this is done, an outer corner member 42 is secured in place by fastening means 43.

90 In Fig. 14 another type of corner made from the blocks shown in Figs. 6 and 7 is illustrated. This corner block is also shown in Fig. 15. It comprises an L-shaped member 45 which has plane outer surfaces 46. The L member has a plurality of interlocking members 47 thereon held in spaced relation thereto by fastening members 48. Each of the interlocking members 47 on the L-shaped members 45 at the corner are engaged by a strip 50 of metal or other material, the ends 51 of which are bent around locking members 27 of the wall so that the corner blocks are held in assembled relation.

95 In Fig. 16 I show a block comprising a front member 52 and a pair of interlocking rear members 53 which are secured to the front member by fastenings means 54. The interlocking members 53 project above and below the top and bottom of the front member 52. In Fig. 17 a rear view of the wall made from the blocks shown in Fig. 16 is disclosed. This wall it will be noted has a continuous front face 52 with the joints 55 between the blocks staggered in adjoining courses, and with the locking members arranged in spaced relation. Blocks of the type shown in Figs. 16 and 17 may be held in place by a filling of concrete or other cementitious material shown at 56 which 100 serves to unite the blocks to prevent shift-

ing thereof. This concrete 56 may be held in place while setting by planks 57 which will be removed after the concrete has hardened.

5 In Figs. 18, 19 and 20 I show a block of the same type as that previously described wherein front members 60 and rear members 61 are provided. The front and rear members are connected by fastening members 62 10 to interlocking members 63. The member 63 as shown in Fig. 10 projects above and below the top and bottom of the front and back members. In Fig. 18 the front member is of greater width than the rear members 15 so that these members when interlocked may form a stationary curved wall 64 as shown in Fig. 21. Such a wall as this may be made into a silo or other building as desired.

20 From the foregoing description it will be apparent that I have provided an improved unit building construction which can be made very economically, and which can be erected at a minimum of cost.

25 Having thus described my invention, I claim:

1. A building tile comprising a front and back member, locking members arranged between said front and back members near each side of the front and back members, said locking members extending above the top and below the bottom of the front and back members and being narrower than the distance between the front and back members, and means to secure the front and back members to the locking members.

2. A building tile adapted to be placed in a wall and comprising two rectangular portions constituting the front and the back of the tile, a pair of connecting members, one disposed at each side of said front and back and spaced therefrom but connected thereto by means spaced from the top of the front and back, said connecting members projecting above said front and back.

3. A building tile adapted to be placed in a wall and comprising a front and back

member, said front and back members being united to each other near each edge thereof by central locking members and fastening members, said locking members being disposed within the end edges of said front and back members and projecting above and below the front and back members, said locking members being narrower than the distance between the inner face of the front and back members.

4. A wall constructed from a plurality of similar units, each unit comprising a rectangular front and back member, locking members narrower than the distance between the inner faces of the front and back members secured to the inner surface of the front and back members, the locking members of adjacent units interfitting, said locking member projecting upwardly beyond the top of the unit.

5. A wall constructed from a plurality of blocks, each of said blocks comprising two members constituting the front and the back, and a pair of interlocking members, one disposed within the ends of the front and back and near each side of said front and back members and connected to those members, the total length of said interlocking members being less than the height of the front, said connecting means being adapted to coact to support the front and back when the parts are assembled, said front forming a continuous surface, and a filling of cementitious material between the front and back and engaging the interlocking members.

6. A wall comprising a plurality of blocks arranged in interlocked relation, each of said blocks comprising front and back members and locking members, said locking members being arranged intermediate said front and back members and a stay member engaging the locking members of different blocks to hold the blocks in assembled position.

In testimony whereof, I hereunto affix my signature.

ELMER E. VAN WIE.
